UNITED STATES PATENT OFFICE.

ALOIS REIMANN, OF ZIZKOV-PRAGUE, AUSTRIA-HUNGARY.

INSULATING COVERING FOR PIPES.

No. 903,316.

Specification of Letters Patent. Patented Nov. 10, 1908.

Application filed July 22, 1908. Serial No. 444,785.

To all whom it may concern:

Be it known that I, ALOIS REIMANN, a subject of the Emperor of Austria-Hungary, residing at Zizkov-Prague, Bohemia, Austrian Empire, have invented certain new and useful Improvements in Insulating-Coverings for Pipes, of which the following is a specification.

The subject of my invention is an insulating covering for pipes.

The new covering is not only very simple to apply, but has the advantage that the pipes and their connections are protected by a continuous insulating layer, and that in the event of the flange-joints leaking, the steam immediately escapes to the outside without penetrating the insulating material.

In the accompanying drawing, Figure 1 is a longitudinal section through the insulating covering applied to piping. Fig. 2 is a cross section through Fig. 1. Fig. 3 is a longitudinal sectional view showing a modification. Fig. 4 is a cross section through Fig. 3. Fig. 5 is a longitudinal section through the casing employed in insulating pipe-joints. Fig. 6 is a part cross section through Fig. 5.

In making the insulating covering of the actual pipe 1, a cord 2 of asbestos or other suitable material, which has previously been immersed in or painted over with water-glass, is coiled round the pipe in a spiral of high pitch. After the water-glass has well dried in, filamentous glass (spun glass, or glass wool), hereinafter briefly referred to as spun glass, 3 in loose, open condition is uniformly applied between the coils 2 until the spaces are filled up, that is to say, until the layer 3 of spun glass is at the same level as the cord 2. Hereupon the spun glass 3 and cord 2 are sheathed with paper 4, which has been externally coated once or more with water-glass. This paper sheath 4 hardens and protects the spun glass layer 3. In addition to the simple paper sheath corrugated paper, painted over with water-glass on the outside, may be employed, which renders the protective sheathing considerably stronger. This covering 2, 3, 4 is sufficient for ordinary insulating purposes. If, however, a still more effective insulation is required, the paper sheath 4 is first allowed to dry, and over this first insulating covering 2, 3, 4 a second similar covering is applied, consisting as before of a cord 2', spun glass 3', and a protective sheath of paper 4'. If desired, one

or more extra insulating coverings may be applied to this covering 2', 3', 4'. The coils 2 should be of high pitch, and in the event of two or more insulating coverings being employed, the coils 2, 2' should not lie coincident one on the other, but should be wound so to say one between the other, for instance as shown in Fig. 3. The end of each length of covering is closed by the cord 2 being wound round the pipe to form a ring, such as 5 shown at 5, 5'.

At the pipe joints, made by bolted flanges 6, 7, a two-part flange-box or casing 8 of well-known construction is employed, in conjunction with a cage of wires 9, 8', 9" secured thereto. Each wire is bent six times at right angles, so that there are three sections, namely, a central section 9, bridging the flanges 6, 7, and two lateral sections 9', 9" which lie in the spaces between the flanges 7 and the rings 5. The sections 9' are longer than the sections 9", so that on opening the box 8 and removing the nuts the flange-bolts can be drawn out without the insulating covering of the pipes having to be disturbed.

To the interior of the wire cage there is secured a split troughed ring, 10, which, when the box 8 is closed, bears with its edges 11 against the flanges 6, 7 covering over the interstice 12 between the latter. In the event, therefore, of the packed joint leaking, the escaping steam enters the trough 10 and from here is conducted to the outside by the outlet pipe 13. In this manner a leaky joint can be at once detected by the issuing steam, which, however, can not enter the non-conducting covering material. The space between the box 8 and the wire cage is packed with spun glass 3". The various wires of the cage are connected with the box 8 at each end, and owing to their resilience the split ring 10 secured to them is firmly pressed against the flanges at its edges 11.

Having thus described my invention, I claim as new—

1. In combination, a pipe, a cord coated with water-glass coiled round the pipe, spun glass filling the spaces between the cord coils, and paper coated on the outside with water-glass sheathing the cord and spun glass, substantially as described.

2. In combination, a pipe, and a plurality of superposed insulating coverings surrounding the same, and each comprising a coiled cord coated with water-glass, spun glass fill-

ing the spaces between the cord coils, and paper coated on the outside with water-glass sheathing the cord and spun glass, substantially as described.

5 3. In combination, coupled flanged pipes, a cord coated with water-glass coiled round each pipe, spun glass filling the spaces between the cord coils, and paper coated on the outside with water-glass sheathing the cord
10 and spun glass, a cage consisting of a plurality of wires bridging the flanges and extending for a certain distance at each side, a casing inclosing the cage and secured to it at the ends, a split troughed ring pressed by the
15 cage against the flanges and covering the interstice between them and having an exit pipe extending to the outside of the casing, and spun glass filling the space between the cage and the casing and forming with the in-

sulation of the pipes a continuous covering, 20 substantially as described.

4. An insulating covering for the joints of flanged pipes, comprising a cage consisting of a plurality of wires each bent to present a bridge and two lateral sections, a casing enclosing the cage and having the ends of the wires connected to it, a split troughed ring located in the cage and secured to the bridges and presenting an exit pipe extending to the outside of the casing, and spun 25 glass filling the space between the cage and the casing, substantially as described.

In testimony whereof I affix my signature in presence of two witnesses.

ALOIS REIMANN.
